FIG. 4

FIG. 6

FIG. 1 is a developed plan view of a shirt cuff showing my new design;

FIG. 2 is a developed plan view thereof as it appears from the other side;

FIG. 3 is a plan view thereof as it appears folded with the tab buttoned;

FIG. 4 is an end view of the shirt cuff shown in FIG. 3 looking in the direction of the arrows 4—4;

FIG. 5 is a top perspective view of the cuff shown in FIG. 3 as it appears folded down and partially buttoned;

FIG. 6 is a perspective view of the shirt cuff as it appears in wearing position.

The embroidered oval-shaped outline appearing adjacent the tab in FIG. 2 serves as a frame for enclosing a monogram and like indicia.

I claim:

The ornamental design for a shirt cuff, substantially as shown and described.
